UNITED STATES PATENT OFFICE.

CHRISTOPHER OFFENHAUSER, OF PHILADELPHIA, PENNSYLVANIA.

DRIER AND EVAPORATOR.

1,249,177.

Specification of Letters Patent.

Patented Dec. 4, 1917.

Application filed July 8, 1917. Serial No. 179,393.

To all whom it may concern:

Be it known that I, CHRISTOPHER OFFENHAUSER, a citizen of the United States, residing in Philadelphia, Pennsylvania, have invented new and useful Improvements in Driers and Evaporators, of which the following is a specification.

One object of this invention is to provide a novel form of rotary machine for extracting evaporating or concentrating liquids, rendering fat or the like, or drying solid material, which shall be of such construction as to require but a relatively small power for its operation and necessitate but a minimum of attention and repairs.

A further object of the invention is to provide a machine of the above noted type which shall include a novel arrangement and construction of drums for respectively containing the material under treatment and for heating the same, together with a scraper of novel form and method of operation;—the apparatus being particularly designed with a view to the prevention of clogging when certain material such as tankage, abattoir by-products or the like are being evaporated or concentrated.

I also desire to provide a relatively efficient, simple and substantial form of rotary drying or evaporating apparatus which shall include a novel arrangement of drums and conduits for conducting away objectionable gases or vapors produced during the operation.

It is further desired to provide a machine of the character described with novel means for insuring continuous engagement between the scraper and the stationary drum; the invention also contemplating such a disposition of the scraper as will aid in the agitation of the material under treatment.

These objects and other advantageous ends I secure as hereinafter set forth, reference being had to the accompanying drawings, in which,

Figure 1 is a side elevation partly in vertical section, illustrating a machine constructed according to my invention; and

Fig. 2 is a transverse vertical section on the line 2—2, Fig. 1.

In the above drawings, 1 represents a pair of base castings, each providing bearings for supporting rollers 2 and on these is ro-

tatably mounted a cylindrical drum arranged with its longitudinal axis substantially horizontal and having the central parts of its ends or heads 12 open, there being supporting tracks or tires 13 on said drum for engagement with said rollers. The drum 11 has mounted on it in any suitable manner an annular rack or gear 14 driven from a suitable source of power through a pinion 15 supported in any desired manner, though obviously other mechanism may be employed for turning it without departing from my invention. Said drum is provided, preferably in its cylindrical portion, with one or more openings of which the single one shown is closed by a door 16 through which material to be dried may be introduced and the product resulting from such material removed. Within the drum and projecting radially inward from its interior surface are a series of longitudinally extending shelves 7, preferably though not necessarily mounted on angle sections attached to the drum structure.

Adjacent and outside of the base castings 1 for the rollers are a pair of supporting standards or columns 4 which carry an inner drum 5 in a position substantially coaxial with the outer drum 11. This inner drum has a smooth external cylindrical surface and is made with heads 17 from each of which projects a casting 3 non-rotatably engaging and supported by the adjacent supporting standard 4. At least one of these head castings is made tubular for the passage of a pipe 6 through which a heating medium such as steam may be introduced, the other one of said castings having a second pipe 18 through which condensed water may be withdrawn. Obviously this second pipe may be omitted if desired and the pipe 6 be used both for the admission of steam and for the withdrawal of water.

For removing material collecting on the stationary drum 5, I provide an elongated knife or scraper 8, having a relatively sharp edge resting upon the cylindrical surface of said drum and while said scraper may be made in a single section engaging the drum, it is preferably divided into three sections 30—31—32, in staggered relation to each other, 120° apart around said inner drum. Each section of the scraper or blade is sup-

ported on two or any suitable number of brackets or braces 9 mounted on the inner surface of the rotary drum 11, being shown in the present instance as carried on or bolted to the angle irons whereby the lifting and agitating shelves 7 are connected to the drum 11. Each of said brackets preferably includes a suitable form of incised spring 33 so mounted as to at all times yieldingly press the scraper blade 8 into the closest engagement with said drum. Obviously the braces 9 may themselves be made of spring material and be so adjusted as to perform the functions of the springs 33, which could then be omitted. In any case the invention involves the provision of a spring device so acting on the scraper blade as to maintain it in constant engagement with the inner drum surface. As shown, the scraper blades or knives are adjustably mounted on the brackets 9 which for this purpose are slotted for the passage of the blade retaining bolts so as to permit said blade or blades being moved toward or from the drum.

For the purpose of carrying away the vapors generated during the operation of the machine, I provide either or both ends of the apparatus with a flue or conduit 10, each of which is rigidly mounted on or supported by one of the castings 3. Each of these conduits includes a vertically extending portion projecting from the casting 3 which carries it, to within a short distance of the topmost part of the inner surface of said drum. This inner portion is connected to the outer part of the conduit or flue by a portion which is concentric with the casting 3 and extends through the opening in the center of the end of the drum 11. This outer portion of either or both of the conduits is connected to a stack, exhaust fan or any desired apparatus for withdrawing the vapors or gases from the interior of the drum 11, though it is to be noted that in some cases one of said flues may be connected to a source of heated air and caused to deliver this to the interior of the rotary drum when it is desired to assist in or hasten the evaporation or drying of the material under treatment.

It is understood that each of the conduits makes a sliding fit with the adjacent end of the rotary drum 11 so that there is practically no escape of gases, and the use of a stuffing box is avoided.

Under conditions of operation the material to be concentrated, evaporated or otherwise treated is introduced into the drum 11 through the opening which is closed by the door 16, and after the latter has been locked, said drum is caused to rotate on its rollers 2 by power applied through the pinion 15 to its gear ring 14 or by any other suitable driving device. At the same time steam or other heating medium is introduced to the

stationary inner drum 5 through the pipe 6, and as the drum 11 is turned, the liquid therein is raised or agitated by the shelves 7 and is delivered in larger or smaller quantities over the surface of the stationary drum 5. Owing to the high temperature at which the latter is maintained, this liquid is rapidly evaporated or concentrated and the vapors generated are drawn off into the flue 10.

At the same time the solid material lodging on or formed upon the cylindrical surface of the drum 5 is cut or scraped therefrom by the blade 8 which is maintained by its springs in intimate contact with the drum surface, and it is obvious that relatively little power is required for this purpose in view of the comparatively small diameter of this drum and of the large rotative force exerted upon the blade 8. If tankage or glue waters such as liquor from cooking tanks or bone boiling vats are being treated with a view to obtaining them in solid form, the operation is continued until such liquid is evaporated to dryness, and it is obvious that even if it assumes a syrupy or gummy consistency, there is no danger of clogging the machine, since said material has practically no tendency to adhere to the inner surface of the drum 11 and the shelves, because these are at a comparatively low temperature and because it cannot collect upon the exterior surface of the drum 5 owing to the scraping or cutting action of the blade or blade sections 8. Upon the completion of the operation the solid material is discharged through the door 16.

It is obvious that the above described machine is particularly advantageous for use in concentrating various liquids as well as for treating fat-containing materials for the purpose of rendering such fat. It is likewise especially adapted for the treatment of liquids which it is desired to absorb in powdered solid material, since the desired end may be obtained without danger of such material becoming permanently attached to the heating surface and thus stopping the successful and efficient operation of the machine.

Obviously the evaporating or concentrating action in any case takes place in an efficient manner and at a high speed, since the heating surface provided by the inner drum is continuously cleaned or freed from the solid material resulting from the evaporation of the liquid. Owing to the fact that the shelves 7 and also the scrapers raise the material under treatment and agitate it though lifting but relatively small amounts thereof, the power required for rotating the drum 11 is materially less than is the case with drying or concentrating machines having the same capacity but of the construction at present employed.

While the gases or vapors generated during operation may ordinarily pass out of the machine through the two flues, I may hasten any drying or evaporating process by forcing heated air through one of said flues into the outer drum, thereby supplying heat in addition to that supplied by the inner drum.

I claim:

5. The combination in a drier or evaporator of a rotary drum; a non-rotatable drum within said first drum; a scraper carried by the first drum and operative upon the surface of the inner drum; with means for turning the rotary drum. 70
10. The combination in a drier or evaporator of a rotary drum; a non-rotatable drum within said first drum; a scraper carried by the first drum and operative upon the surface of the inner drum; with means for turning the rotary drum. 75
15. The combination in a drier or evaporator of a rotary drum; a non-rotatable drum within said first drum; a scraper carried by the first drum and operative upon the surface of the inner drum; with means for turning the rotary drum, said scraper being adjustable toward and from said inner drum. 80
20. The combination in a drier or evaporator of a rotary drum; a non-rotatable drum within said first drum; a scraper carried by the first drum and operative upon the surface of the inner drum; means for turning the rotary drum; with means for yieldingly pressing the scraper toward the inner drum. 85
25. The combination in a drier or evaporator of a rotary drum; a non-rotatable drum within said first drum; a scraper carried by the first drum and operative upon the surface of the inner drum; means for turning the rotary drum; with means for yieldingly pressing the scraper toward the inner drum. 90
30. The combination in a drier or evaporator of a rotary drum; a non-rotatable drum within said first drum; a scraper carried by the first drum and operative upon the surface of the inner drum; means for turning the rotary drum; with incased springs mounted to yieldingly press the scraper toward the surface of the inner drum. 95
35. The combination in a drier or evaporator of a rotary drum; a non-rotatable drum within said first drum; brackets mounted on the rotary drum; a scraper carried by said brackets in engagement with the non-rotatable drum; and springs interposed between the rotary drum and the scraper for yieldingly pressing the latter into engagement with said non-rotatable drum. 100
40. The combination in a drier or evaporator of a rotary drum; a non-rotatable drum within said first drum; brackets mounted on the rotary drum; a scraper carried by said brackets in engagement with the non-rotatable drum; and springs interposed between the rotary drum and the scraper for yieldingly pressing the latter into engagement with said non-rotatable drum. 110
45. The combination in a drier of a supporting structure; a drum carried thereby; means for supplying a heating medium to said drum; a second drum substantially coaxial with said first drum and inclosing the same; means for rotating said second drum; and means for removing solid material from the outer surface of the first drum. 115
50. The combination in a drier of a supporting structure; a drum carried thereby; means for supplying a heating medium to said drum; a second drum substantially coaxial with said first drum and inclosing the same; means for rotating said second drum; and means for removing solid material from the outer surface of the first drum. 120
55. The combination in a drier of a supporting structure; a drum carried thereby; means for supplying a heating medium to said drum; a second drum substantially coaxial with said first drum and inclosing the same; means for rotating said second drum; and means for removing solid material from the outer surface of the first drum, consisting of a blade carried by the second drum. 125
60. The combination in a drier of a supporting structure; a drum carried thereby; means for supplying a heating medium to said drum; a second drum substantially coaxial with said first drum and inclosing the same; means for rotating said second drum; and means for removing solid material from the outer surface of the first drum. 130
65. The combination in a drier of a supporting structure; a drum carried thereby; means for supplying a heating medium to said drum; a second drum substantially coaxial with said first drum and inclosing the same; means for rotating said second drum; and means for removing solid material from the outer surface of the first drum. 135
70. The combination of supporting means; a drum non-rotatably carried thereby; means for heating said drum; supporting rollers; a second drum substantially coaxial with the first drum and rotatably mounted on said rollers; means for turning the second drum; and means for removing solid material from the exterior surface of the first drum. 75
75. The combination of a drum having a cylindrical exterior surface; means for heating said drum; a second drum rotatably mounted and substantially coaxial with and outside of the first drum; means within the second drum for raising the material therein and directing it toward the first drum; and means for scraping the surface of said first drum. 80
80. The combination of a drum having a cylindrical exterior surface; means for heating said drum; a second drum rotatably mounted to be substantially coaxial with and outside of the first drum; means within the second drum for raising the material therein and directing it toward the first drum; and means for scraping the surface of said first drum; consisting of a sharp-edged blade bearing upon said drum surface and supported by the second drum. 85
85. The combination in a drier or evaporator of a rotary drum; a second drum inside said first drum; means for heating said inner drum; and at least one flue for conducting the gases from the first drum, the same including a portion extending through the central part of one end of the outer drum and a second portion extending upwardly within the outer drum from said first portion; with means for agitating material within the rotary drum. 90
90. The combination in an evaporator or drier of a supporting structure; a drum carried thereby; a second drum rotatably supported substantially coaxial with said first drum and having a central opening in one end; means for heating the first drum; with a flue supported by the first drum, extending through the opening of the second drum, and projecting upwardly toward the highest point of the same; with means for agitating material within the rotary drum. 95
95. The combination in an evaporator or drier of a supporting structure; a drum carried thereby; a second drum rotatably supported substantially coaxial with said first drum; a conduit for introducing heated air to the rotatable drum; a second conduit for carrying off gases generated within said drum; and a scraper carried by the rotatable drum in engagement with the cylindrical surface of the second drum. 100
100. The combination in an evaporator or drier of a supporting structure; a drum carried thereby; a second drum rotatably supported substantially coaxial with said first drum; with a scraping device operative on 105

the external surface of the first drum and made in a number of substantially parallel sections spaced apart around said drum.

15. The combination in an evaporator or 5 drier of a supporting structure; a drum carried thereby; a second drum rotatably supported substantially coaxial with said

first drum; with a scraping device operative on the external surface of the first drum and made in a number of substantially parallel 10 sections spaced apart around said drum and arranged in staggered relation thereon.

In witness whereof I affix my signature.
CHRISTOPHER OFFENHAUSER.
